WASHING MACHINE

John Broatch, Vancouver, British Columbia,
Canada

Application April 18, 1939, Serial No. 268,554

5 Claims. (Cl. 141—9)

My invention relates to improvements in washing machines, the object of which is to provide a washer which is capable of use for washing clothes or washing dishes, glasses and the like. Another object is to produce the washing effect on clothes by pulsating the water intermittently through the body of the clothes, so that no violent clothes disturbance takes place and that the clothes are not rubbed against themselves or the basket in which the washing takes place. A further object is to provide means whereby a relatively small amount of hot water is required for washing dishes and the washing is effected either by pulsation or by throwing water up and around the contents of the basket while imparting slow rotation to said basket.

The invention consists essentially of a washing receptacle having a flexible water bag in communication therewith and means for compressing the bag to force its water content into the washing receptacle, as will be more fully described in the following specification and shown in the accompanying drawing, in which:

Fig. 1 is an elevational view of the invention.

Fig. 2 is a plan view.

Fig. 3 is a transverse sectional view of the invention taken on the line 3—3 of Figure 2 showing the clothes washing basket.

Fig. 4 is a transverse sectional view taken on the line 4—4 of Figure 2 showing the dish washing basket and the valve jet structure.

Fig. 5 is a fragmentary view of the valve jet structure optionally usable in dish washing.

In the drawing like characters of reference indicate corresponding parts in each figure.

The numeral 1 indicates a cylindrical washer or tank having side walls 2, a flanged upper rim 3 and a bottom wall 4. Formed in the side wall 2 adjacent the bottom wall 4 is a rectangular opening 5 which provides communication between the tank 1 and a flexible water bag 6.

The water bag 6 is preferably of rubber and is arcuate in plan to lie in substantial contact with the wall 2 and is of greater length than the opening 5. The bag is set in horizontal position so that water poured into the tank will enter freely into the bag to fill it.

Mounted from the wall 2 is a motor 7 preferably having an inbuilt reduction gear, not shown, and a drive shaft 8, which shaft is provided with a worm 9 meshing with a worm wheel 10 upon a vertical shaft 11. The drive shaft 8 is fitted with a suitable coupling 12, to which a flexible shaft and rotary brush, not shown, may

be attached for cleaning out pots and pans by mechanical means.

A crank disk 14 is secured to the base of the shaft 11 which is connected through a connecting rod 15 to a swinging arm 16. The swinging arm is pivotally mounted on a pin 17 and is carried between upper and lower bearings 18 and 19 which extend from the tank wall 2. To the free end of the arm 16 a thrust plate 20 is pivotally connected which bears against the water bag 6 to collapse it and cause the water to surge from the bag to the tank.

Mounted upon the upper end of the shaft 11 is a crank disk 21 having a crank pin 22 upon which a pawl 23 is mounted. This pawl is provided with a leaf spring 24 which bears against an abutment 25 for the purpose of holding the pawl up to its work.

The tank 1 is provided preferably with two baskets, one for dish washing which is generally indicated by the numeral 26, and one for clothes washing which is generally indicated by the numeral 27. The device as shown in Figures 1 and 4 is fitted with the basket 26.

The basket 26 is a wire structure having any desired form of racks or devices, not shown, for the purpose of supporting crockery and glassware in a convenient position for washing. The basket 26 is provided with a peripheral rim 28 which is adapted to bear upon the rim 3 of the tank 1 and to rotate thereupon. The rim 28 is provided with ratchet teeth 29 which are progressively engaged by the pawl 23 as the crank disk 21 rotates to impart intermittent rotation to the basket within the tank.

The basket 27 is preferably of sheet metal, having a perforated bottom wall 31 and upper and lower rows of perforations respectively numbered 32 and 33 in its side walls. A soft rubber gasket 38 surrounds the lower periphery of the basket to cause the water to pass through the apertured bottom wall 31.

Demountably secured about the opening 5 in the tank wall is a valve jet structure 36 consisting of a plate 37, see Figure 5, having an opening 38 substantially conforming to that of the opening 5. The opening 38 is divided by vertical ribs 39 which pivotally support a series of channel shaped flaps 40 on a pin 41 which is disposed approximately one-third of the distance 50 from the upper edge of the flaps, so that as the water bag 6 is distended the flaps are swung by the water flow thereto into a substantially horizontal position, thus providing a free water passage from tank to water bag. When the water

- bag is collapsed, the flaps 40 assume their substantially vertical position and the water from the bag is forced upwardly in a series of jets at relatively high velocity and substantially in the direction indicated in dotted line as at X in Figure 4, to wash the crockery disposed in the basket 26. When this valve jet structure is used, a small amount of water only is required to wash the contents of the basket.
- 5 10 When using the device for dish washing, the articles to be washed are placed in the basket 26 and preferably the valve jet structure 36 is put in position. Hot water is put into the tank to the height of the bottom of the basket and the motor 15 is started, which causes the bag 6 to be alternately collapsed or squeezed and to fill with water from the tank. Water is thrown upwards through the basket to wash the contents on each squeezing of the bag and is returned to the bag as 20 the thrust plate 20 is moved away from the side of the tank. Following each spurt of water upwards into the dishes, the pawl 23 engages a tooth 29 of the basket rim 28 and moves the basket rotationally upon its vertical axis, so that 25 the water from the valve jet structure will strike the contents of the basket from a different lateral angle at each spurt.
- When using the device for washing clothes, the basket 27 is preferred and the valve jet structure 30 is removed. The clothes are placed in the basket and are preferably held against inflation by placing a foraminous cover 42 upon them. On the reciprocation of the thrust plate 20 and the surge of water through squeezing of the water bag and the tank, the water will be urged through the clothes upwardly and as the bag is distended the water will gravitate again through said clothes to wash them. The clothes will not be materially disturbed, consequently there will be no wear due to washing action.
- What I claim as my invention is:
1. A washing machine comprising a tank having an opening adjacent its base, a water bag connected with said tank and adapted to be supplied

with water from the tank through said opening, a valve structure interposed in said opening for admitting water to the bag to substantially the full bore of the opening and for diverting the water in an upward direction from the bag to the tank as the bag is compressed.

2. A washing machine comprising a tank having an opening adjacent its base, a water bag connected with said tank and adapted to be supplied with water from the tank through said opening, a valve structure interposed in said opening for admitting water to the bag to substantially the full bore of the opening and for restricting the opening and diverting the water in an upward direction from the bag to the tank as the bag is compressed.

3. A washing machine comprising a tank having an opening adjacent its base, a water bag communicating with the tank through said opening, a shaft, an arm having a thrust plate adapted to engage the bag, a driving connection between the shaft and the arm, said connection consisting of a crank upon the shaft and a connecting rod extending from the crank to the arm to impart reciprocatory movement to the thrust plate and compress the water bag against the side of the tank.

4. A washing machine comprising a tank having a peripheral wall and an opening at the base of the wall, a bag mounted on the outside of the tank and in communication therewith through said opening, and means for collapsing the bag against the peripheral wall to force water from the bag to said tank.

5. A washing machine comprising a tank having a peripheral wall and an elongated horizontal opening at the base of said peripheral wall and a horizontal bag mounted entirely outside the tank and in communication therewith through said opening, and means for collapsing the bag against the peripheral wall to force water from the bag to said tank.

JOHN BROATCH.
